WARP STOP MOTION FOR LOOMS

Application filed May 25, 1927. Serial No. 194,178.

This invention relates to improvements in warp stop motions and it is the general object of the invention to provide means whereby such a motion may be readily adaptable to varying conditions of warp in a loom.

In warp stop motions of the type set forth in Patent No. 1,265,112 issued to Regan there is generally employed a non-circular oscillating rod which extends through slots formed in the upper ends of the drop wires. The tops of these slots are restricted so that when a drop wire falls due to a fault of the warp the rod is held against oscillation to stop the loom. With a warp stop motion of this type it is desirable that the distance between the oscillating detector rod and the restricted part of the drop wire slot be as small as possible. The reason for this is that if the warp thread should break at a point distant from the warp stop motion and the broken end be supported by neighboring warp threads an interval of time will lapse before the drop wire will be lowered into operative position with respect to the detector rod. Obviously, the greater the distance between the narrow part of the slot and the detector rod the greater the length of time required for the drop wire to fall onto the rod. On the other hand, the top of the slot should be sufficiently above the detector rod so that a small amount of temporary slackness due to uneven letting-off can occur in the warp without bringing the narrow part of the slot in stopping relation with respect to the rod.

When weaving three or four thread georgette it is found that the broken warp thread is sufficiently stiff to support a light drop wire for such a length of time as will spoil the fabric being woven and it is therefore desirable to have the distance between the restricted part of the slot and the detector rods as small as possible. It so happens that the conditions under which georgette is woven regarding shedding, and the drawing of the warp ends and the number of harnesses used make it possible to have the drop wires in a relatively low position such as is necessary to secure the short distance between the drop wire and the narrow part of the slot.

On the other hand, certain other fabrics

such as satin are woven with a warp which is not as stiff as that used for georgette and a broken warp thread will therefore bend easily under the weight of the drop wire to lower the latter into stopping position earlier than 55 would be the case with the three or four thread Georgette warp. It is found that the weaving conditions of satin with regard to the draw of the warp and the number of harness frames used make it necessary to have 60 less space between the separator bars and the detector rods. This means that the drop wires should be relatively higher than with georgette but inasmuch as the filling is lighter the same drop wire will fall into stopping 65 position as soon as though it were used on a Georgette warp with the wire in relatively lower position. It is an important object of my invention to provide means for varying the position of the drop wire with respect to 70 the detector rods so as to meet the conditions mentioned in connection with different kinds of fabric such as georgette and satin.

It is found that when a large number of harness frames are used the warp threads extending either from the whip roll or the warp beam forwardly to the harness frames is spread out in the form of a fan in a vertical plane so that the drop wires in the front bank are higher than those in the rear bank with 75 the result in certain instances that the bottom of the slot in the top of the drop wires of the front bank strike the bottom of the associated detector rod and prevent the same from moving upwardly as far as would be necessary to allow 80 the warp threads to lie in a straight line. The result of this is to cut the warp threads which are pushed up against the drop wires and it is a further object of my invention to compensate for the spread of the warp 85 threads due to a large number of harness frames so that the proper relation will exist between the drop wires and the detector rods.

Some fancy fabrics are woven from two beams, the principal beam supplying the 90 body of the warp and the additional beam or beams supplying warp for decorative effects. These additional warps are not infrequently under less tension than are the warps for the main body of the fabric. The warp stop mo- 95 100

tion, however, can make no distinction between the respective warp threads and must therefore be set to accommodate the slack threads. If the loom be set to weave a fabric 5 having no slack threads the separator bars and hence the drop wires will be in lowest position for the reasons already given. If the character of fabric being woven be changed so as to require certain of the warp 10 threads to be slack it is found that the drop wires supported by said slack threads would be too low with resultant unnecessary stopping of the loom due to the fact that there is insufficient distance between the oscillating 15 detector rods and the restricted part of the slot in the drop wire. Under these conditions it is necessary to provide some means for raising all of the warp threads in order that the drop wires on the slack threads may be properly placed with respect to the detector rods. It is a still further object of my invention to 20 provide for such adjustment as will permit the same stop motion to weave fabrics all the warp threads of which are normally taut and 25 also fabrics wherein certain of the warp threads may be relatively slack.

When warp stop motions are applied to relatively wide looms it is desirable to hold the centers of the separating bars and detector 30 rods in proper alignment and to accomplish this result there is usually employed a so-called separator. It is a further object of my invention to provide an improved form of separator made with adjustable parts 35 which will permit the distance between the separator bars and the detector rods to be changed as the character of fabric being woven is changed.

With these and other objects in view which 40 will appear as the description proceeds, my invention resides in the combination and arrangement of parts hereinafter described and set forth in the claims.

In the accompanying drawings wherein 45 I have shown one embodiment of my invention,

Fig. 1 is a vertical section taken through the loom and showing my invention applied thereto,

50 Fig. 2 is an enlarged rear elevation taken in the direction of arrow 2, Fig. 1, certain parts being shown in section and other parts being broken away for the sake of clearness,

55 Fig. 3 is a vertical section on line 3—3 of Fig. 2 showing the separator bars in relatively low position for the weaving of a fabric such as georgette, or one with tight warp,

Fig. 4 is a view similar to Fig. 3 but with 60 the separator bars raised to the position they should occupy when such a fabric as satin is being woven, or when the warp has slack threads,

Fig. 5 is a vertical section on line 5—5 65 of Fig. 2 showing the separator,

Fig. 6 is a detailed top plan view taken in the direction of arrow 6, Fig. 2, and,

Fig. 7 is a detailed top plan view taken in the direction of arrow 7, Fig. 2.

Referring more particularly to Figs. 1 and 70 2 I have shown a loom frame 10 having a bottom shaft 11 to which is secured a cam 12 which may receive a complete rotation every second pick of the loom. A cam lever 13 pivoted at 14 to the frame cooperates with 75 the cam to give upright rod 15 a vertical reciprocation once every two picks of the loom. Said rod is connected at the upper end thereof with a lever 16 pivoted as at 17 to a warp stop motion head 18 of the form illustrated in patent to Holmes No. 1,360,638. By means of the mechanism set forth in the 80 said patent detector rods 19 which are non-circular in cross section are given an oscillating movement at periodic intervals. The 85 drop wires 20 employed are as shown in the aforesaid patents, said drop wires being shown more clearly herein in Figs. 3 and 4 as having a slot in the upper end thereof the 90 top of which is restricted as at 21 and the lower portion of which is relatively wide as indicated at 22. An open slot 23 at the 95 bottom of each drop wire provides means for supporting the same on its respective warp thread.

The knock-off mechanism comprises a rod 24 connected to the head 18 as set forth in said Holmes patent and the forward end of said rod is attached to shipper mechanism indicated generally at 25. Under normal operation the rod 15 will receive a periodic vertical reciprocation the effect of which will be to oscillate the non-circular detector rods 19. So long as the drop wires are all in raised position the detector rods are free to 105 rock on their axes and the shipper mechanism remains in running position, but when one of the drop wires falls the corresponding 110 detector rod will be held against oscillation by the restricted portion 21 of the slot of the fallen drop wire and the rod 24 will be given a forward movement to rock the shipper handle to loom stopping position. This 115 mechanism is well understood and is thought to be sufficiently described in the aforesaid Regan and Holmes patents so that further description herein is unnecessary. The matter thus far described does not enter into my 120 present invention and may be of the usual form.

In carrying my present invention into effect I provide improved means for varying the distance between the drop wires and the detector rods and this I accomplish by providing movable supports for the separator bars to the end that the latter may be given a plurality of vertical positions. The warp of a loom ordinarily lies above and is positioned by the separator bars and of course 130

the drop wires being supported by the warp are indirectly positioned by the separator bars. Accordingly, stands 30 are secured to the loom frame and have longitudinally adjustably secured thereto L-shaped supporting angle arms 31 each having a portion 32 which extends through and is secured to a hub 33. As shown in Fig. 2 the hub on the left hand side is a part of the head 18 whereas the hub on the right is part of a secondary head 18^a. In this way each head of the warp stop motion is held in fixed position with respect to the loom. It is to be understood that the detector rods 19 oscillate about centers which are fixed with respect to the heads 18 and 18^a and consequently the angle arm supports 31.

Each head has projecting inwardly therefrom a pair of lugs 40 each of which is perforated to receive a threaded rod 41. The lower end of each rod is secured to a separator bar support 42 and each threaded rod is provided with adjusting nuts 43 above and below the corresponding lugs 40. Each bar support is provided with a plurality of slots 44 which receive the ends of the separator bars 45. Said bars are held in spaced relation and position the lower ends of the drop wires. The warp W passes forwardly from the whip roll R and is led over the separator bars 45 so that the latter as shown in Figs. 3 and 4 indirectly determine the vertical position of the drop wires. If desired, certain of the separator bars may be narrower than others but I consider it desirable to have the outside bars as wide as any of the others and the bars of smaller dimension will ordinarily be located between said outside bars. It is not necessary to employ this construction but it has been found convenient in practice.

The so-called separator shown at 50 and set forth more particularly in Figs. 2, 5 and 7 comprises a body portion 51 provided at the lower side thereof with a plurality of slots 52 which receive the aforesaid separator bars 45. A depending ear 53 has pivoted thereto a bottom cap 54 the right hand end of which as viewed in Fig. 5 is forked as at 55, see more particularly Fig. 2. Said forked end receives a screw 56 pivoted as at 57 to the body portion 51 and a winged nut 58 provides means for detachably securing the bottom cap in proper position with the separators held against the bars.

The body portion has a pair of upstanding horns 59 which are received by sockets 60 formed on the ends of the detector rod guide 61, said guide being provided with a plurality of upwardly opening slots 62 which are larger than the detector rods but sufficiently small to hold the latter against undue lateral displacement. By means of set screws 63 carried by the guide 61 the latter may be held in adjusted vertical position on the horns 59. It is sufficient for my present purpose to pro-

vide means for varying the location of the guide 61 with respect to the body portion 51 and I do not wish to be limited necessarily to the particular means shown herein for securing this adjustment.

As previously stated it is desirable to change the relation between the detector rods 19 and the restricted part 21 of the drop wires 20. As shown in Fig. 4 the motion is set for warp conditions such as attend the weaving of satin or where a few slack warp threads are used. To meet these conditions the separator bar supports 42 will be raised and held in relatively high position by the nuts 43 and the threaded rods 41. The result of this adjustment is to keep the narrow slot portions 21 the proper distance above the detector rods 19.

If at a later time the same loom to which the warp stop motion is applied is to be employed for weaving georgette or a fabric requiring all the warp threads to be tight the parts will be moved to the relative position shown in Fig. 3. If this were not done and the parts remained as shown in Fig. 4 the tightening of the warp would raise the drop wires so that the distance between the narrow part of the slot 21 and the detector rods 19 would be greater than is desirable and a break in the warp occurring several inches from the warp stop motion might require too much time for the corresponding drop wire to fall into stopping engagement with the associated detector rod. The supports 42 are therefore lowered to compensate for the relatively higher position of the drop wires due to the tighter warp and in this way operative relation is maintained between the drop wires and the detector rods. Corresponding changes can be made in the separator to accommodate the relative positions of the detector rods and the separator bars.

From the foregoing it will be seen that I have provided means for maintaining the proper relation between the drop wires and the detector rods and that it is possible by the use of my present invention to maintain the narrow parts 21 of the drop wire slots at the proper minimum distance above the detector rods irrespective of the character of cloth being woven. It will further be seen that I have provided a separator of an improved form such as is set forth in Figs. 5 and 7 which can be varied to meet the conditions brought about by the adjustment of the separator bars with respect to the detector rods. It is to be understood that I do not wish to be limited to the particular constructions set forth herein whereby the separator bars may be adjusted relatively to the detector rods.

Having thus described my invention it will be apparent that changes and modifications may be made therein by those skilled in the art without departing from the spirit and

scope of the invention and I do not wish to be limited to the details herein disclosed, but what I claim is:

1. In a warp stop motion having drop wires, detector rods to cooperate with fallen drop wires, separator bars located normally below the detector rods, a frame to hold the detector rods, a support for the separator bars, a threaded rod extending upwardly from each end of the separator bar support and having operative engagement with the frame, and means to hold each bar with respect to the frame, each threaded rod capable of adjusting the corresponding end of the support relatively to the frame while the other end of the support remains stationary with the frame.
2. In a warp stop motion having drop wires, detector rods to cooperate with fallen drop wires, separator bars located normally below the detector rods, a frame to hold the detector rods, a support for the separator bars, a threaded rod extending upwardly from each end of the support and through the frame, a nut on the upper end of each threaded rod whereby each threaded rod may be moved with respect to the frame independently of the other rod.
3. In a warp stop motion having drop wires, detector rods to cooperate with fallen drop wires, separator bars located normally below the detector rods, a frame to hold the detector rods, a support for the separator bars, a threaded rod extending upwardly from each end of the support and through the frame, a nut on the upper end of each threaded rod whereby each threaded rod may be moved with respect to the frame independently of the other rod, and a second nut on each rod to engage the frame and prevent upward movement of the corresponding threaded rod.

In testimony whereof I have hereunto affixed my signature.

45 GEORGE H. SHUTT.
